PROCESS CARTRIDGE
REMANUFACTURING METHOD

BACKGROUND OF THE INVENTION

1. Field of the Invention

The present invention relates to a method of remanufacturing a process cartridge detachably mountable to a main body of an electrophotographic image forming apparatus.

2. Related Background Art

Conventionally, in an image forming apparatus using the electrophotographic image forming process, there is adopted a process cartridge system in which an electrophotographic photosensitive drum and process means acting on the electrophotographic photosensitive drum are integrated into a cartridge, which is detachably mountable to the main body of the electrophotographic image forming apparatus.

In the process cartridge system, the user himself can perform apparatus maintenance without relying on a serviceman, thereby achieving a marked improvement in terms of operability.

In the process cartridge system, an image is formed on a recording medium by using developer. Thus, as image formation is repeated, the developer is gradually consumed. When the developer has been consumed to a degree that image formation is no longer possible, the process cartridge is of no commercial value.

In order to remanufacture a process cartridge with frame connecting portions where resin bonding is effected, there has been proposed a technique according to which after the resin-bonded portions are cut, the frames are re-connected, with a spacer being held between the bonded portions (see US-2002-0159788).

SUMMARY OF THE INVENTION

The present invention aims to further improve the above conventional technique.

It is an object of the present invention to provide a simple process cartridge remanufacturing method.

Another object of the present invention is to provide a process cartridge remanufacturing method which makes it possible to prepare for the market again a process cartridge the developer of which has been consumed to a degree that an image of a quality satisfying the user cannot be formed any more, making the process cartridge of no commercial value.

Still another object of the present invention is to provide a process cartridge remanufacturing method for a process cartridge detachably mountable to an electrophotographic image forming apparatus and including: an electrophotographic photosensitive drum; a drum frame supporting the electrophotographic photosensitive drum; a developing roller adapted to develop an electrostatic latent image formed on the electrophotographic photosensitive drum by using a developer; a developing frame supporting the developing roller and having a developer containing portion containing the developer; a first cover member for securing the developing frame and the drum frame in position at one longitudinal end of the drum frame; a second cover member for securing the developing frame and the drum frame in position at the other longitudinal end of the drum frame; and a drum supporting member which serves to support the electrophotographic photosensitive drum on the drum frame and which is fixed by a screw to a screw hole provided at the other longitudinal end of the drum frame, the drum frame and the developing frame being connected to the second

2

cover member by pouring molten resin into resin bonding portions provided in the drum frame, the developing frame, and the second cover member, the process cartridge remanufacturing method including: (a) a first cover detaching step 5 of detaching, at one longitudinal end of the process cartridge, the first cover member from the drum frame and the developing frame; (b) a second cover detaching step of detaching, at the other longitudinal end of the process cartridge, the second cover member from the drum frame 10 and the developing frame; (c) a drum supporting member detaching step of detaching the drum supporting member from the drum frame; (d) a frame separating step of separating the developing frame and the drum frame; (e) a developing roller detaching step of detaching the developing 15 roller from the developing frame; (f) a developer re-filling step of filling the developer containing portion with the developer from a developer supply port provided on the developing frame exposed by detaching the developing roller from the developing frame; (g) a developing roller 20 fixation step of mounting a developing roller to a developing frame; (h) a drum mounting step of mounting, at the one longitudinal end, an electrophotographic photosensitive drum to a drum frame; (i) a first frame connecting step of securing the drum frame and the developing frame in 25 position at the one longitudinal end by a first cover member; (j) a second frame connecting step of securing the drum frame and the developing frame in position at the other longitudinal end by a second cover member; (k) a drum 30 supporting member temporary mounting step of temporarily mounting a drum supporting member to support the electrophotographic photosensitive drum at the other longitudinal end of the drum frame; and (l) a second cover member mounting step of mounting the drum supporting member and the second cover member to the drum frame by mounting a fixation member to a mounting hole provided in the second cover member by using the screw.

These and other objects, features and advantages of the present invention will become more apparent upon consideration of the following description of the preferred embodiments of the present invention taken in conjunction with the accompanying drawings.

BRIEF DESCRIPTION OF THE DRAWINGS

45 FIG. 1 is a sectional view of an electrophotographic image forming apparatus according to an embodiment of the present invention;

50 FIG. 2 is a sectional view of a process cartridge according to an embodiment of the present invention;

FIG. 3 is a perspective view of a support frame according to the embodiment of the present invention and portions in the vicinity thereof;

55 FIG. 4 is a sectional view of a developing roller according to the embodiment of the present invention and portions in the vicinity thereof;

FIG. 5 is a sectional view of a magnetic seal portion and portions in the vicinity thereof;

60 FIGS. 6A and 6B are perspective views illustrating a fusion-bonding portion of a developing frame and a developer frame;

FIG. 7 is a perspective view of a developing apparatus unit according to the embodiment of the present invention;

65 FIG. 8 is a partial perspective view of the developing apparatus unit according to the embodiment of the present invention;

FIG. 9 is an exploded top view of a photosensitive member unit according to the embodiment of the present invention;

FIG. 10 is a perspective view of the photosensitive member unit according to the embodiment of the present invention;

FIG. 11 is an exploded perspective view of the photosensitive member unit according to the embodiment of the present invention;

FIG. 12 is a perspective view of a drive transmission member of an electrophotographic image forming apparatus and portions in the vicinity thereof;

FIG. 13 is a perspective view illustrating the construction of the photosensitive member unit;

FIG. 14 is a perspective view of a process cartridge according to the embodiment of the present invention;

FIG. 15 is an exploded perspective view illustrating how the developing frame and the developer frame are assembled;

FIGS. 16A and 16B are partial sectional views illustrating a fusion-bonding portion;

FIG. 17 is a partially exploded perspective view illustrating how a developing blade is assembled;

FIG. 18 is an exploded perspective view illustrating how a support frame is assembled;

FIG. 19 is an exploded perspective view illustrating how a developing roller is assembled;

FIG. 20 is a partial perspective view illustrating a portion where a first cover member, a developing apparatus unit, and a photosensitive member unit are connected together;

FIG. 21 is a partial perspective view illustrating a portion where a second cover member, the developing apparatus unit, and the photosensitive member unit are connected together;

FIGS. 22A, 22B, and 22C are sectional views and a perspective view of a portion where the second cover member and the developer frame are resin-bonded;

FIGS. 23A, 23B, and 23C are sectional views and a perspective view of a portion where the second cover member and the drum frame are resin-bonded;

FIG. 24 is an exploded perspective view illustrating a process for detaching the first cover member;

FIG. 25 is an exploded perspective view illustrating a process for detaching the second cover member;

FIGS. 26A, 26B, and 26C are sectional views illustrating a method of effecting separation at a portion where the second cover member and the developer frame are resin-bonded to each other;

FIGS. 27A, 27B, and 27C are sectional views illustrating a method of effecting separation at a portion where the second cover member and the drum frame are resin-bonded to each other;

FIG. 28 is an exploded perspective view illustrating how the developing roller is detached from the developing apparatus unit;

FIG. 29 is an exploded perspective view illustrating how the developing blade is detached;

FIG. 30 is an exploded perspective view illustrating how the support frame is detached;

FIG. 31 is a sectional view illustrating how the developer frame is re-filled with developer;

FIG. 32 is a sectional view of the process cartridge according to the embodiment of the present invention;

FIG. 33 is an exploded perspective view illustrating how the photosensitive drum is detached;

FIG. 34 is an exploded perspective view illustrating how the photosensitive drum is detached;

FIG. 35 is an exploded perspective view illustrating how a charging roller is detached;

FIG. 36 is a perspective view illustrating how the photosensitive member unit is re-assembled;

FIG. 37 is a perspective view illustrating how the photosensitive drum is mounted;

FIG. 38 is a perspective view illustrating how the photosensitive drum is mounted;

FIG. 39 is a perspective view illustrating a frame connecting process;

FIG. 40 is a perspective view illustrating a frame connecting process;

FIGS. 41A, 41B, and 41C are sectional views illustrating a resin-bonded portion connecting process;

FIG. 42 is a schematic diagram illustrating how the process cartridge is attached to the apparatus main body;

FIGS. 43A and 43B are sectional views of a screw mounting hole for mounting a centering shaft to the drum frame and portions in the vicinity thereof; and

FIGS. 44A and 44B are perspective views of a fastening member.

DESCRIPTION OF THE PREFERRED EMBODIMENTS

In the following, examples of the best mode for carrying out the present invention will be described in detail with reference to the drawings and embodiments. The functions, materials, configurations, and positional relationships of the components as described in the following embodiments should not be construed restrictively unless otherwise specified. Further, the materials, configurations, and the like of the components described below are common to the embodiments unless otherwise noted.

Embodiment 1

In the following, a process cartridge to which a process cartridge remanufacturing method of the present invention is suitably applicable, and an electrophotographic image forming apparatus to which the process cartridge is detachably mountable, will be described with reference to the drawings.

Here, the electrophotographic image forming apparatus is an apparatus which forms an image on a recording medium by using an electrophotographic image forming system. Examples of the electrophotographic image forming apparatus include an electrophotographic copying machine, an electrophotographic printer (a laser printer, an LED printer, or the like), a facsimile apparatus, and a word processor.

The process cartridge is obtained by integrating a charging means, a developing means or a cleaning means, and an electrophotographic photosensitive member into a cartridge, which is detachably mountable to the main body of the electrophotographic image forming apparatus.

Alternatively, at least one of a charging means, a developing means, and a cleaning means and an electrophotographic photosensitive member are integrated into a cartridge, which is detachably mountable to the main body of the electrophotographic image forming apparatus.

In the following description, the transverse direction of the process cartridge is the direction in which the process cartridge is attached to and detached from the main body of the electrophotographic image forming apparatus, and coincides with the direction in which the recording medium is conveyed. The longitudinal direction of the process cartridge is a direction crossing (substantially perpendicular to) the direction in which the process cartridge is attached to and

detached from the main body of the electrophotographic image forming apparatus; it is a direction parallel to the surface of the recording medium and crossing the direction in which the recording medium is conveyed.

(General Construction of the Electrophotographic Image Forming Apparatus)

Referring to FIG. 1, a laser beam printer constituting an example of the electrophotographic image forming apparatus (hereinafter referred to as the "image forming apparatus") will be described. An image forming apparatus main body P, shown in FIG. 1, forms an image on a recording medium 4 (e.g., a recording paper sheet, OHP sheet, or cloth) by an electrophotographic image forming process.

The surface of a photosensitive drum 10, which is a drum-shaped electrophotographic photosensitive member, is uniformly charged by a charging roller 11. A laser beam L corresponding to image information is applied to the charged photosensitive drum 10 from an optical means 1, and a latent image corresponding to the image information is formed on the photosensitive drum 10. The latent image formed on the photosensitive drum 10 is developed by a developing means described below, with the result that a toner image is formed on the photosensitive drum 10.

The recording medium 4, contained in a sheet feeding cassette 6a, is conveyed by a pickup roller 6b, a conveying guide 6c, and a registration roller pair 6e in synchronism with the formation of the toner image. Then, the recording medium 4 passes a nipping portion formed by a transfer roller 3, to which a fixed voltage is applied, and the photosensitive drum 10. At this time, the toner image on the photosensitive drum 10 is transferred to the recording medium 4. The recording medium 4 to which the toner image has been transferred passes a conveying guide 6f and is conveyed to a fixing means 5.

The fixing means 5 has a driving roller 5c and a fixing roller 5b containing a heater 5a. By applying heat and pressure to the recording medium 4 passing the nipping portion of the driving roller 5c and the fixing roller 5b, the transferred toner image is fixed to the recording medium 4. Thereafter, the recording medium 4 is conveyed by a discharging roller pair 6i to be discharged onto a discharge tray 7.

(Process Cartridge)

Next, a process cartridge C will be described with reference to FIG. 2.

As shown in FIG. 2, the process cartridge C is obtained by connecting a developing apparatus unit A and a photosensitive member unit B with each other.

The developing apparatus unit A has a developer frame 21 containing toner, a developing roller 20 which supplies toner to an electrostatic latent image formed on the photosensitive drum 10 to thereby form a visible image, a developing blade 29 which imparts triboelectrification charge to the toner to form a toner layer on the surface of the developing roller 20, and the like.

Further, at a lower opening between the developing roller 20 and a developing roller frame 50, there is provided a spouting prevention sheet 25 for preventing toner on a lower portion of the developing roller 20 from leaking.

The above-mentioned developing means sends out the toner in the developer frame 21 to the developing roller 20 through rotation of toner carrying members 23a and 23b. Then, the developing roller 20, which contains a stationary magnet 28, is rotated, and the thickness of the toner layer on the developing roller 20 is regulated by a blade 29e inte-

grally formed with or glued to the developing blade 29. In the process, triboelectrification charge is imparted to the toner.

The developing roller 20 is pressed against the photosensitive drum 10 by an urging spring 32 (see FIG. 7) while maintaining a fixed clearance between itself and the photosensitive drum 10 through the intermediary of a spacer runner 26. The toner on the surface of the developing roller 20 is supplied to the photosensitive drum 10.

10 The supplied toner is transferred to the photosensitive drum 10 in correspondence with the electrostatic latent image, whereby a toner image is formed. Further, in the vicinity of the developing roller 20, there is rotatably mounted a toner agitating member 24 for circulating the toner in the developing chamber.

15 The photosensitive member unit B has the photosensitive drum 10 for forming an electrostatic latent image, the charging roller 11 for uniformly charging the surface of the photosensitive drum 10, a cleaning blade 14 for scraping off, 20 from the surface of the photosensitive drum 10, residual toner adhering to the photosensitive drum 10 without being transferred to the recording medium 4, a waste toner container 12 for storing the toner scraped off, and the like.

In FIG. 2, the photosensitive drum 10 rotates clockwise.

25 The charging roller 11, to which a fixed voltage is applied, comes into contact with the photosensitive drum 10, thereby uniformly charging the surface of the photosensitive layer of the photosensitive drum 10.

30 Next, the laser beam L corresponding to image information from the optical means 1 is applied to the surface of the photosensitive drum 10 through an exposure opening 2, and an electrostatic latent image is formed on the photosensitive drum 10. Thereafter, a toner image is formed on the photosensitive drum 10 by the developing means.

35 The transfer roller 3 is provided in the main body P of the image forming apparatus, and undergoes application of a voltage of a polarity reverse to that of the toner image. After the toner image formed on the photosensitive drum 10 is transferred to the recording medium 4, the residual toner on the photosensitive drum 10 is removed by the cleaning blade 14. Here, the cleaning blade 14 scrapes off the residual toner remaining on the photosensitive drum 10 by a blade 14a held in contact with the photosensitive drum 10, and collects the toner in the waste toner container 12.

40 (Housing Construction of the Process Cartridge C)

Next, the housing construction of the process cartridge C of this embodiment will be described.

45 The process cartridge C of this embodiment is obtained by connecting together into a cartridge the developing apparatus unit A, which is formed by connecting together the developer frame 21 and the developing roller frame 50 and to which a support frame 40 as the developing frame holding the developing blade 29 is connected, and the photosensitive member unit B, which has a drum frame 13 accommodating the photosensitive drum 10, the charging roller 11, the cleaning blade 14, and the like.

50 Further, the process cartridge C can be detachably attached to a cartridge attachment means provided in the main body P of the image forming apparatus.

55 (Developing Apparatus Unit A)

As shown in FIG. 2, the developing apparatus unit A is composed of the developer frame 21 and the developing roller frame 50 constituting the developing frame.

60 As shown in FIGS. 3 and 4, at the ends of the support frame 40, there are arranged a first end cover 42 and a second end cover 43. The support frame 40, the first end

cover 42, and the second end cover 43 are secured to each other, and in this state, hold the developing roller 20 and the developing blade 29.

The developing roller 20 is rotatably supported at both ends by the first end cover 42 and the second end cover 43 through the intermediation of bearings 27.

Further, rotatably provided at both ends of the developing roller 20 are spacer runners 26 substantially coaxial with the developing roller 20 and having an outer diameter larger than the outer diameter of the developing roller 20 by a dimension corresponding to the requisite gap between the photosensitive drum 10 and the developing roller 20.

The developing blade 29 is fit-engaged with positioning bosses 40a and 40b of the support frame 40 for positioning, and is secured in position by screws 95. The distal end of the blade 29e is in contact with the developing roller 20.

At one end of the developing roller 20, there are provided a developing roller gear 72 for transmitting torque to the developing roller 20, a detachment preventing member for the developing roller gear 72, and a stationary member 73 for determining the phase of the stationary magnet 28 contained in the developing roller 20.

Further, at the longitudinal ends of the developing blade 29, there are provided toner regulating members 100 that scrape off the toner at the end portions of the developing roller 20 to move it longitudinally inwards.

Further, between the developing blade 29 and the toner regulating members 100, there are provided thin-plate-like scrapers 101. The distal ends 101d of the scrapers 101 are in contact with the spacer runners 26. The scrapers 101 scrape off dirt, such as toner, adhering to the spacer runners 26, thus preventing a fluctuation in the distance between the photosensitive drum 10 and the developing roller 20. Further, at the longitudinal ends of the developing roller 20, there are arranged magnetic seals 60.

As shown in FIG. 5, each magnetic seal 60 has a plurality of magnetic poles on the surface 60a opposed to the surface of the developing roller 20, and serves as a seal means that attracts toner by a magnetic circuit formed between it and the stationary magnet 28 in the developing roller 20. The developing roller 20 and the magnetic seals 60 are fixed to the same support frame 40, so that even when the developing roller 20 is driven by the outer periphery of the photosensitive drum 10 to move the support frame 40, it is possible to set the clearance between the developing roller 20 and the magnetic seals 60 to a fixed dimension. Thus, it is possible to effect toner sealing in a satisfactory manner at both ends of the developing roller 20 by the magnetic seals 60.

As shown in FIGS. 6A and 6B, the developing roller frame 50 and the developer frame 21 are fixed to each other through fusion bonding (described below) of fusion-bonding ribs 50e and 50f provided on the upper and lower sides of an opening 50g of the developing roller frame 50 and fusion-bonding planes 21g and 21h provided on the upper and lower sides of an opening 21k of the developer frame 21.

As shown in FIG. 7, a toner filling port 21a is provided in a side surface of the developer frame 21. After filling the developer frame 21 with toner through the toner filling port 21a, the toner filling port 21a is stopped by a toner cap 22 to effect tight closing to thereby prevent leakage of toner.

The support frame 40 is installed in the developing roller frame 50. The first end cover 42 fixed to the support frame 40 is equipped with a rocking arm 46 having a rocking hole 47 at an end thereof. The developing roller frame 50 is equipped with a support arm 55 having a fixation hole 56

(see FIG. 19) at an end thereof. The first end cover 42 and the developing roller frame 50 are rotatably connected by a fixation pin 83.

Clearance fit allowing rotation is effected between the rocking hole 47 of the first end cover 42 and the fixation pin 83, and close fit is effected between the fixation hole 56 of the developing roller frame 50 and the fixation pin 83.

As shown in FIG. 8, slide planes 43a and 43b determining the sliding direction are provided parallel to each other substantially on the upper and lower surface of the second end cover 43. On the portions of the developing roller frame 50 opposed to the slide planes 43a and 43b, there are provided guide planes 50a and 50b, with minute clearances therebetween. Due to the slide planes 43a and 43b and the guide planes 50a and 50b, the second end cover 43 can slide in a fixed direction.

As shown in FIG. 7, an urging spring 32 is provided between the first end cover 42 and the developing roller frame 50. Similarly, an urging spring 32 (not shown) is also provided between the second end cover 43 and the developing roller frame 50. The urging springs 32 press the developing roller 20 provided on the support frame 40 against the photosensitive drum 10, with a fixed clearance due to the spacer runners 26 therebetween.

(Photosensitive Member Unit B)

The construction of the photosensitive member unit B will be described with reference to FIGS. 9, 10, and 11. A driving side flange 10a is mounted to one end of the photosensitive drum 10, and a non-driving side flange 10b is mounted to the other end of the photosensitive drum 10. The driving side flange 10a has a coupling protrusion 10a1, a shaft portion 10a2, and a gear portion 10a3 for driving a developing roller gear (not shown). The non-driving side flange 10b has an inner peripheral portion 10b 1 for insertion of a centering shaft 31, and a gear portion 10b2 for driving a transfer roller gear (not shown) of the main body P of the image forming apparatus.

The photosensitive drum 10 is supported as follows: on the right-hand (drive input) side, the drum bearing 30 is fixed to the side portion 13a of the drum frame 13 by means of a screw 99, with the inner peripheral portion 30a of the drum bearing 30 and the shaft portion 10a2 of the driving side flange 10a being rotatably fit-engaged with each other.

In the drum bearing 30, an outer diameter portion 30c coaxial with the inner peripheral portion 30a protrudes longitudinally inwards. The outer diameter portion 30c is fit-engaged with an arcuate cutout portion 13o provided in the drum frame 13. The width of the opening of the cutout portion 13o is larger than the diameter of the shaft portion 10a2.

The coupling protrusion 10a1 of the driving side flange 10a is formed as a twisted prism.

As shown in FIG. 12, when the process cartridge C is attached to the main body P of the image forming apparatus, the coupling protrusion 10a1 is fit-engaged with a drive transmission member 503 having a twisted polygonal hole 503a provided in the main body P of the image forming apparatus and receives the torque. At the same time, the driving side flange 10a is pulled toward the drive transmission member 503 for alignment.

Further, as shown in FIGS. 9 and 10, on the left-hand (non-drive-input) side, the centering shaft 31 is fixed to the side portion 13b of the drum frame 13 by means of a screw 98, with the centering shaft 31 being rotatably fit-engaged with the inner peripheral portion 10b 1 of the non-driving side flange 10b.

As shown in FIG. 11, to support the charging roller 11, inner walls 13d on the inner side of the drum frame 13 (of which the left-hand side one is omitted in the figure because of a symmetrical configuration) have bearing guides 19. Bearings 15 are movable along the bearing guides 19.

Further, one end of an urging member 82 is mounted to a boss 15a of each bearing 15, and the other end thereof is in contact with a seat surface 13g of the drum frame 13. Thus, an urging force is constantly exerted in the direction of the photosensitive drum 10.

Further, due to a stopper 19a provided on each bearing guide 19, there is no fear of the bearings 15 being detached from the bearing guides 19. The charging roller 11 is supported by the drum frame 13 by mounting a core 8a to the bearings 15, and is brought into contact with the surface of the photosensitive drum 10 by the urging members 82. Here, the urging members 82 are compression coil springs.

As shown in FIG. 2, the frame member of the drum frame 13 consists of an integral molding (not shown) of resin material, or is formed by coupling a drum lower frame 121 with a drum upper frame 122.

In this embodiment, the drum frame 13 is formed by integrating the drum lower frame 121 and the drum upper frame 122 by ultrasonic welding bonding.

Further, as shown in FIGS. 2 and 13, the cleaning blade 14 and the drum frame 13 are arranged such that a rib 122a of the drum upper frame 122 covers the surface of a blade support portion 14b on the side where the photosensitive drum 10 is mounted. Sealing is effected by pouring foam elastomer 123 into the gap between the blade support portion 14b and the rib 122a.

As shown in FIG. 14, the developing apparatus unit A and the photosensitive member unit B are placed in position by means of a first cover member 80 and a second cover member 81 on either longitudinal side surface thereof. Further, the developing apparatus unit A and the photosensitive member unit B are integrally connected with and fixed to the first cover member 80 and the second cover member 81 by means of screws and resin bonding described below to form the process cartridge C.

As shown in FIG. 32, in the longitudinal direction of the process cartridge C, the positioning of the first cover member 80 and the second cover member 81 is determined by the photosensitive member unit B. That is, the first cover member 80 and the second cover member 81 are longitudinally in contact with the photosensitive member unit B by a dimension S. In contrast, while the developing apparatus unit A is longitudinally in contact with the first cover member 80, there is a gap of a dimension W1 between the developing apparatus unit A and the second cover member 81. This is, as stated above, due to the fact that the positioning of the first cover member 80 and the second cover member 81 is determined by the photosensitive member unit B. Thus, to bond the developing apparatus unit A and the second cover member 81, molten resin is preferably poured into a bonding portion 81c to fill the gap. Further, taking into account the operational efficiency, the second cover member 81 and the photosensitive member unit B are preferably also bonded by molten resin (hereinafter referred to as resin bonding). This makes it possible to uniformly effect the bonding of the second cover member 81 to the developing apparatus unit A and the photosensitive member unit B by resin bonding. A detailed description of the resin bonding will be given below.

(Method of Assembling the Developing Apparatus Unit A)

A method of assembling a part of the developing apparatus unit A according to this embodiment of the present invention will be described.

First, a method of fusion-bonding the developing roller frame 50 and the developer frame 21 will be described with reference to FIGS. 6, 15, 16A, and 16B.

The developing roller frame 50 has the fusion-bonding ribs 50e and 50f on the upper and lower sides of the opening 50g thereof. Fusion portions 50h are provided at the distal ends of the fusion-bonding ribs 50e and 50f (FIG. 6A). On the upper and lower sides of the opening 21k of the developer frame 21, the fusion-bonding planes 21g and 21h are provided (FIG. 6B).

As shown in FIG. 15, between the developing roller frame 50 and the developer frame 21, there are provided an elastic seal member 36 at one longitudinal end and an elastic seal member 37 at the other longitudinal end so as to overlap the fusion-bonding ribs 50e and 50f. The developing roller frame 50 and the developer frame 21 are placed in position and connected together by respectively fit-engaging positioning bosses 50i and 50j of the developing roller frame 50 with positioning holes 21i and 21j of the developer frame 21.

As shown in FIG. 16A, at this time, the fusion portion 50h at the distal end of the fusion-bonding rib 50e (50f) of the developing roller frame 50 is in contact with the fusion-bonding plane 21g (21h) of the developer frame 21. When these portions in contact with each other are caused to undergo ultrasonic vibration by an ultrasonic vibrator, the fusion portion 50h is fused and fusion-bonded to the fusion-bonding plane 21g, 21h, as shown in FIG. 16B. As a result, the developing roller frame 50 and the developer frame 21 are firmly connected to each other to form the developing frame.

Next, the mounting of the magnetic seals 60 and the developing blade 29 will be described. As shown in FIG. 17, one of the magnetic seals 60 is inserted into a recess 40e provided at one longitudinal end of the support frame 40. Then, the magnetic seal 60 is pressurized by the developing blade 29 through the intermediation of a seal member 18. In this process, temporary positioning is effected on the magnetic seal 60. However, since the magnetic seal 60 is pressurized through the intermediation of the seal member 18, there is no fear of the magnetic seal 60 being detached from the support frame 40. A similar assembly is effected at the other longitudinal end (not shown).

(Developing Blade Mounting Process)

As shown in FIG. 17, positioning is effected on the developing blade 29 by fit-engaging it with positioning bosses 40a and 40b (the latter of which is shown in FIG. 18) of the support frame 40.

A toner regulating member 100 is placed in position by fit-engaging a positioning rib 100c with a fixation hole 29d of the developing blade 29 and by fit-engaging a positioning hole 100a with the positioning boss 40a of the support frame 40.

A scraper 101 is placed in position by fit-engaging positioning holes 101a and 101c respectively with the positioning boss 40a of the support frame 40 and the positioning rib 100c of the toner regulating member 100.

The developing blade 29, the toner regulating member 100, and the scraper 101 are collectively fastened to the support frame 40 by a common screw 95. A similar assembly is conducted on the other side (not shown).

11

(Support Frame Installation Process)

As shown in FIG. 18, a positioning hole 40g of the support frame 40 is fit-engaged with a positioning boss 52 of the developing roller frame 50 to thereby effect longitudinal positioning. Then, the support frame 40 is installed at the opening of the developing roller frame 50.

(Developing Roller Fixation Process)

As shown in FIG. 19, the developing roller 20 with spacer runners 26 rotatably provided at both ends thereof is arranged on the support frame 40. Then, a first end cover 42 with a bearing 27 installed therein is fixed to one end of the support frame 40 by fit-engaging a positioning boss (not shown) with a positioning hole 40h of the support frame 40 and fastening them by a screw 92. Similarly, a second end cover 43 with the bearing 27 installed therein is fixed to the other end of the support frame 40 by fit-engaging a positioning boss 43c with a positioning hole (not shown) of the support frame 40 and fastening them by a screw 93. At this time, both ends of the developing roller 20 are rotatably secured to the first end cover 42 and the second end cover 43 respectively through the intermediation of the bearings 27.

In the developing roller fixation process, the positioning boss of the first end cover 42 and the positioning boss 43c of the second end cover 43 are fit-engaged with positioning holes 60b (see FIG. 5) of the magnetic seals 60, thereby effecting positioning on the magnetic seals 60.

Thereafter, a developing roller gear 72 is inserted into one end portion of the developing roller 20, and a fixation member 73 is secured in position on the first end cover 42.

(Support Frame Connection Process)

The rocking hole 47 provided in the rocking arm 46 of the first end cover 42 is rotatably connected with a fixation hole 56 provided in the support arm 55 of the developing roller frame 50 by means of a fixation pin 83.

(Method of Assembling the Process Cartridge C)

As shown in FIGS. 20 and 21, the developing apparatus unit A and the photosensitive member unit B are installed so as to face each other.

A pin 80a for placing the first cover member 80 in position on the developing apparatus unit A is fit-engaged with a positioning hole 50a provided in the developing roller frame 50, and a hole 80b for placing the first cover member 80 in position on the photosensitive member unit B is fit-engaged with the outer diameter portion 30b of the drum bearing 30 of the photosensitive member unit B, whereby the positional relationship between the developing apparatus unit A and the photosensitive member unit B is determined. Thereafter, the developing apparatus unit A and the photosensitive member unit B are connected with the first cover member 80 by means of screws 96.

Similarly, a pin 81a for placing the second cover member 81 in position on the developing apparatus unit A is fit-engaged with a positioning hole 50b provided in the developing roller frame 50, and a hole 81b for placing the second cover member 81 in position on the photosensitive member unit B is fit-engaged with the centering shaft 31 of the photosensitive drum 10 of the photosensitive member unit B, whereby the positional relationship between the developing apparatus unit A and the photosensitive member unit B is determined. Thereafter, the developing apparatus unit A and the photosensitive member unit B are fixed to the second cover member 81 by resin bonding as follows.

As shown in FIG. 21, the second cover member 81 and the developer frame 21 have in their opposing surfaces resin

12

bonding portions 81c and 21c. And, as described with reference to FIG. 32, molten resin 90 is poured into the gaps of the resin bonding portions 81c and 21c, whereby fixation is effected.

FIGS. 22A, 22B, and 22C are diagrams illustrating the construction of the resin bonding portion. FIG. 22A is a sectional view of the bonding portion, FIG. 22B is a sectional view of the bonding portion with molten resin poured therein, and FIG. 22C is a perspective view showing the configuration of the bonding resin poured.

As shown in FIGS. 22A and 22B, the resin bonding portion 81c of the second cover member 81 has an inlet port 81d for pouring molten resin 90, a pouring passage 81e, and a substantially cylindrical protrusion 81f forming the bonding portion.

Further, the resin bonding portion 21c of the developer frame 21 of the developing apparatus unit A has a substantially cylindrical protrusion 21d forming the bonding portion, a lightening portion 21f thereof, and a cylindrical portion 21e having an inner diameter larger than the outer diameter of the protrusion 81f.

The molten resin 90 for bonding the second cover member 81 and the developing apparatus unit A to each other is poured from the inlet port 81d of the second cover member 81. The poured molten resin 90 passes the pouring passage 81e to reach the downstream side opening 81g, and then forms a first bonding portion 90a spread in a disc-like fashion in a plane perpendicular to the pouring passage 81e. Thereafter, the poured molten resin 90 forms a second bonding portion 90b between the inner periphery of the protrusion 81f and the outer periphery of the protrusion 21d. As a result, the poured molten resin 90 attains a state as shown in FIG. 22B, whereby the second cover member 81 is firmly fixed to the developer frame 21 of the developing apparatus unit A.

Further, as shown in FIG. 21, the second cover member 81 and the drum frame 13 have in their opposing surfaces resin bonding portions 81h and 13p, and they are fixed to each other by pouring molten resin 91 into the gaps of the resin bonding portions 81h and 13p.

FIGS. 23A, 23B, and 23C are diagrams illustrating the construction of the resin bonding portion. FIG. 23A is a sectional view of the bonding portion, FIG. 23B is a sectional view of the bonding portion with molten resin poured therein, and FIG. 23C is a perspective view showing the configuration of the bonding resin poured.

As shown in FIGS. 23A and 23B, the resin bonding portion 81h of the second cover member 81 has an inlet port 81i for pouring molten resin 91, a pouring passage 81j, and a substantially cylindrical protrusion 81k forming the bonding portion.

Each of the resin bonding portions 13p of the drum frame 13 has a substantially cylindrical protrusion 13q forming the bonding portion, and a cylindrical portion 13r having an inner diameter larger than the outer diameter of the protrusion 81k.

The molten resin 91 for bonding the second cover member 81 and the drum frame 13 to each other is poured from the inlet port 81i of the second cover member 81. The poured molten resin 91 passes the pouring passage 81j to reach the downstream side opening 81l, and then forms a first bonding portion 91a spread in a disc-like fashion in a plane perpendicular to the pouring passage 81j. Thereafter, the poured molten resin 91 forms a second bonding portion 91b between the outer periphery of the protrusion 81k and the inner periphery of the protrusion 13q. As a result, the poured

13

molten resin **91** attains a state as shown in FIG. 23B, whereby the second cover member **81** is firmly fixed to the drum frame **13**.

In this embodiment, the second cover member **81** and the drum frame **13** are resin-bonded to each other because the second cover member **81** and the developer frame **21** are resin-bonded to each other. That is, to fill the longitudinal gap of the second cover member **81** and the developer frame **21**, resin bonding is suitable. And, the connection between the second cover member **81** and the drum frame **13**, which is effected on the same side as the above resin bonding with respect to the longitudinal direction, is also effected through resin bonding, whereby an improvement is achieved in the operational efficiency for the assembly.

In this embodiment, the material of the three frames bonded together, that is, the material of the second cover member **81**, the developer frame **21**, and the drum frame **13** is HIPS (high impact polystyrene). HIPS is also used for the molten resins **90** and **91**.

The material is not restricted to this one. More preferably, however, a resin compatible with the resin of the frame to be bonded is used as the resin to be poured, whereby bonding can be performed effectively. And, it is possible to secure the components of the process cartridge C firmly to each other so that the components may not be detached from each other even when the process cartridge C suffers shock during transportation or when it is dropped.

By the above process, relative positioning is effected on the developing apparatus unit A and the photosensitive member unit B, and they are integrally connected with each other.

(Method of Dismantling the Process Cartridge C)

A method of dismantling and remanufacturing the process cartridge C according to an embodiment of the present invention will be described with reference to FIGS. 24 through **42**.

(Process for Detaching the First and Second Cover Members)

As shown in FIGS. 24 and 25, by removing the screws **96** at one longitudinal end of the process cartridge C, the first cover member **80** is detached from the developing roller frame **50** or the developer frame **21** constituting the developing apparatus unit A, and from the drum frame **13** constituting the photosensitive member unit B.

Further, at the other longitudinal end of the process cartridge C, the resin bonding portions of the drum frame **13** and the developing roller frame **50** or the developer frame **21** are separated, thereby detaching the second cover member **81** from the photosensitive member unit B and the developing apparatus unit A.

For the separation of the resin bonding portions, the following methods are available which are shown in FIGS. 26A, 26B, and 26C and FIGS. 27A, 27B, and 27C.

(1) A method in which a force in the direction indicated by the arrow Y is applied to the second cover member **81** to strip the resin bonding portion or in which the bonding resin is broken to effect separation (FIGS. 26A and 27A).

(2) A method in which the resin bonding portion **81c** of the second cover member **81** is severed at the position indicated by wavy lines **N** (on the outer side of the protrusion **81f**) (FIG. 26B).

(3) A method in which the portion of the second cover member **81** starting from the pouring inlet **81d**, continuing to the pouring flow passage **81e**, and continuing down to the

14

first bonding portion **90a** (the region surrounded by a dashed line **M** in the drawing) is cut away to effect separation (FIG. 26C).

(4) A method in which the resin bonding portion **81h** of the second cover member **81** is severed at the position indicated by wavy lines **D** (outside the protrusion **81k**) (FIG. 27B).

(5) A method in which the portion of the second cover member **81** starting from the pouring inlet **81i**, continuing to the pouring flow passage **81j**, and continuing down to the first bonding portion **91a** (the region surrounded by a dashed line **E** in the drawing) is cut away to effect separation (FIG. 27C).

It should be noted that the method of separating the resin bonding portion is not restricted to the above-mentioned ones.

(Process for Separating the Developer Frame (Developing Roller Frame) and the Drum Frame)

By thus removing the first cover member **80** and the second cover member **81**, the connection between the developer frame **21** (the developing roller frame **50**) and the drum frame **13** is eliminated. As a result, the developing apparatus unit A and the photosensitive member unit B are separated from each other. The separation of the developing apparatus unit A and the photosensitive member unit B from each other facilitates the remanufacturing process described below.

(Method of Dismantling and Remanufacturing the Developing Apparatus Unit A)

Referring to FIG. 28, a process for detaching the developing roller **20** from the separated developing apparatus unit A will be described.

(Process for Pulling Out the Fixation Pin)

The fixation pin **83**, by means of which the first end cover **42** and the developing roller frame **50** are rotatably engaged with each other, is pulled out to eliminate the connection between the developing roller frame **50** and the first end cover **42** to thereby effect separation. Further, the fixation member **73** and the developing roller gear **72**, secured in position to the first end cover **42**, are pulled out.

(Process for Detaching the Developing Roller)

Next, the screw **92**, which fixes the first end cover **42** to the support frame **40**, is removed. Then, the first end cover **42** is removed from the support frame **40** together with the bearing **27**. Similarly, the screw **93**, which fixes the second end cover **43** to the support frame **40**, is removed. Then, the second end cover **43** is removed from the support frame **40** together with the bearing **27**.

By thus removing the first end cover **42** and the second end cover **43**, it is possible to remove the developing roller **20**.

It is also possible to remove the developing roller **20** by removing only one of the first end cover **42** and the second end cover **43**.

(Process for Detaching the Developing Blade and the Toner Regulating Member)

Next, the process for detaching the developing blade **29** from the support frame **40** will be described.

As shown in FIG. 29, after the developing roller **20** is removed from the support frame **40**, the screw **95**, which collectively fastens the developing blade **29**, the scraper **101**, and the toner regulating member **100**, is removed. Similar detachment of the screw **95** is performed on the longitudinally opposite side (not shown). The developing blade **29** is

15

removed together with the scraper 101 and the toner regulating member 100. This allows replacement of components at the time of remanufacture.

(Process for Detaching the Support Frame)

Next, the support frame 40, from which the developing blade 29 has been removed, is detached from the developing roller frame 50 (FIG. 30).

The detachment of the developing blade 29 may also be effected after the support frame 40 is detached from the developing roller frame 50. By detaching the support frame 40, the toner supply opening 51 can be widely exposed, thereby facilitating the developer re-filling process described below.

(Developer Re-Filling Process)

Referring to FIG. 31, the process for refilling the developer frame 21 with developer (hereinafter referred to as toner) T will be described.

First, residual toner in the developer frame 21 is removed by suction, air blowing, or the like from the toner supply opening 51 of the developer frame 21 exposed by detaching the developing roller 20 from the support frame 40. The toner supply opening 51 is open along the longitudinal direction of the photosensitive drum 10, so that suction, air blowing, or the like can be easily effected on the toner. Then, the developer frame 21 is held such that the toner supply opening 51 is on the upper side. The distal end of a funnel 501 is inserted into the toner supply opening 51, and toner T is poured into the funnel 501 from a toner bottle 502.

In this way, the developer containing portion of the developer frame 21 is filled with toner supplied from the toner supply opening 51.

Thereafter, the toner supply opening 51 is covered with a new developer seal member to effect re-sealing, preventing leakage of toner.

It is not always necessary to effect the re-sealing of the toner supply opening 51. It is also possible to perform remanufacture without re-sealing.

Further, this toner filling process can be conducted without removing the support frame 40.

Furthermore, this toner filling process can be conducted without removing the support frame 40 and the developing blade 29.

(Developing Blade Mounting Process)

Assembly is conducted in the same manner as described above under the heading of (Process for Mounting the Developing Blade) of (Method of Assembling the Developing Unit A).

When the developing blade 29 to be mounted again to the support frame 40 is not replaced by a new one, the cleaning and inspection processes described below may be additionally performed.

Before the developing blade 29 is mounted to the support frame 40, any toner adhering thereto is removed by effecting an air blast or the like simultaneously with air suction. After the cleaning, inspection is conducted to make a judgment as to whether remanufacture is possible or not. When it is determined that remanufacture is possible, the developing blade 29 is mounted as it is. When the result of the inspection shows that its performance will not satisfy a predetermined standard, it is replaced by a new one as appropriate.

16

(Developing Roller Fixation Process)

Assembly is conducted in the same manner as described above under the heading of (Support Frame Installation Process) of (Method of Assembling the Developing Apparatus Unit A).

Due to the rubbing contact with the developing blade 29, the developing roller 20 may be worn. In view of this, when statistics show that it is highly possible that replacement of the developing roller 20 is necessary at the time of remanufacture of the process cartridge C, the developing roller 20 is replaced by a new one without conducting inspection, thereby achieving an improvement in operational efficiency.

However, there will be cases in which the developing roller 20 is not replaced by a new one from the viewpoint of achieving an improvement in terms of remanufacturability. In such cases, the following cleaning and inspection processes may be additionally performed.

Any toner adhering to the developing roller 20 is removed by an air blast simultaneously with air suction. Next, the developing roller 20 is inspected again to make a judgment as to whether recycling thereof is possible or not. When it is determined that it can be recycled, the developing roller 20 is mounted as it is. When the inspection result shows that its performance will not satisfy a predetermined standard, the developing roller 20 is replaced by a new one as appropriate.

Further, the inspection of the developing apparatus unit A may be conducted on each component thereof after dismantling it into the developing roller 20, the stationary magnet 28, the bearing 27, the spacer runner 26, the developing roller gear 72, and the like. In this way, it is determined what can be recycled and what cannot, replacing what cannot be recycled by new ones as appropriate.

(Support Frame Connecting Process)

Assembly is conducted in the same manner as described above under the heading of (Support Frame Connecting Process) of (Method of Assembling the Developing Apparatus Unit A).

(Method of Dismantling and Remanufacturing the Photosensitive Member Unit B)

A method of dismantling and remanufacturing the photosensitive member unit B, which has undergone the above-described (Process for Detaching the First and Second Cover Members) and (Process for Separating the Developer Frame and the Drum Frame), will be described.

(Shaft Detaching Process)

As shown in FIG. 34, the screw 98 is removed from the left-hand side portion 13b of the drum frame 13, and the centering shaft 31 is removed from the photosensitive drum 10.

(Bearing Portion Detaching Process)

Similarly, as shown in FIG. 33, the screw 99 is removed from the right-hand side portion 13a of the drum frame 13 to remove the drum bearing 30. Either of the shaft detaching process and the bearing portion detaching processing may be conducted first.

(Photosensitive Drum Detaching Process)

By thus removing the centering shaft 31 and the drum bearing 30, it is possible to remove the photosensitive drum 10 in a direction crossing the longitudinal direction thereof.

The extraction of the photosensitive drum 10 can also be effected solely through the removal of the centering shaft 31. In this case, the process can be shortened. At this time, the photosensitive drum 10 is removed by first shifting the non-driving side thereof (see FIG. 34).

By removing the photosensitive drum 10, it is possible to perform replacement of the photosensitive drum 10 and removal of the toner contained in the waste toner container 12 as described below.

(Charging Roller Detaching Process)

As shown in FIG. 35, the charging roller 11 provided on the inner walls 13d is removed. At this time, the bearing 15 and the urging member 82 may be removed if necessary.

(Cleaning Blade Detaching Process)

As described above, in the drum frame 13 of this embodiment, the drum lower frame 121 and the drum upper frame 122 are integrated with each other by ultrasonic welding bonding.

Further, as shown in FIGS. 2 and 35, the cleaning blade 14 and the drum frame 13 are arranged such that the rib 122a of the drum upper frame 122 covers the photosensitive drum mounting side surface of the blade support portion 14b.

Thus, when detaching the cleaning blade 14 from the drum frame 13, the screw 94 is removed after cutting off the rib 122a by a tool, such as a cutter, an ultrasonic cutter, or a milling cutter (not shown).

By performing this process, the cleaning blade 14 can be detached from the drum frame 13 easily and reliably.

(Developer Removing Process)

Further, after removing the cleaning blade 14, the toner contained in the waste toner container 12, which accommodates the toner removed from the photosensitive drum 10 by the cleaning blade 14, is removed therefrom. Since the cleaning blade 14 is detached, the opening of the waste toner container 12 is large, thus facilitating the removal of the toner.

In the developer removing process, the removal of the toner from the waste toner container 12 is effected by vacuum-sucking the toner from within the waste toner container 12 or by blowing out the toner with compressed air. Further, when suction is conducted simultaneously with the supply of compressed air to the waste toner container 12, the toner is not scattered, and can be advantageously removed with rapidity.

The charging roller detaching process and the cleaning blade detaching process may be omitted if not necessary. Further, the charging roller removing process may be omitted if not necessary.

(Re-Assembly of the Photosensitive Member Unit B)

The cleaning blade 14, the charging roller 11, and the photosensitive drum 10 are mounted in this order to the drum frame 13 to assemble the photosensitive member unit B.

The cleaning blade 14 to be recycled is one accepted based on the inspection. When it cannot be recycled, it is replaced by a new one. As shown in FIG. 36, the cleaning blade 14 is mounted to the drum frame 13 by the screws 94. Then, a fluid material 124 consisting of foam elastomer, adhesive, molten resin, or the like is poured into the gap between the drum frame 13 and the cleaning blade 14 over the entire longitudinal region thereof, thereby effecting sealing.

Next, the core 8a of the charging roller 11 is fit-engaged with the bearings 15. When the bearings 15 and the urging members 82 are removed in the (Charging Roller Detaching Process), the urging members 82 and the bearings 15 are fit-engaged with the bearing guides 19 (not shown) in the inner walls 13d of the drum frame 13, and the core 8a of the charging roller 11 is fit-engaged with the bearings 15.

(Photosensitive Drum Inserting Process)

Next, as shown in FIG. 37, a new photosensitive drum 10 is inserted into the drum frame 13 in a direction crossing the longitudinal direction thereof. Here, when the photosensitive drum 10 is inserted into the drum frame 13, a shaft portion 10a2 provided at one end thereof enters a cutout portion 13o of the drum frame 13.

(Photosensitive Drum Mounting Process)

A drum bearing 30 serving as the bearing portion is mounted to one longitudinal end of the drum frame 13 by a screw 99 so that the shaft portion 10a2 provided at one end of the new photosensitive drum 10 may be supported. At the same time, the centering shaft 31 is mounted to one longitudinal end of the drum frame 13 so that the other end of the new photosensitive drum 10 may be supported.

When the photosensitive drum 10 is detached, with solely the centering shaft 31 removed, the driving side flange 10a of the new photosensitive drum 10 is first inserted into the inner peripheral portion 30a of the drum bearing 30, and the non-driving side is shifted in the direction indicated by the arrow D2 in FIG. 38 to mount the centering shaft 31 to one longitudinal end of the drum frame 13.

(Method of Re-Assembling the Process Cartridge C)

(Frame Connecting Process)

As shown in FIG. 39, the developing apparatus unit A and the photosensitive member unit B are installed so as to be opposed to each other. Then, the pin 80a for placing the first cover member 80 in position on the developing apparatus unit A is fit-engaged with the positioning hole 50a provided in the developing roller frame 50, and the hole 80b for placing the first cover member 80 in position on the photosensitive member unit B is fit-engaged with the outer diameter portion 30b of the drum bearing 30 of the photosensitive member unit B, whereby the positional relationship between the developing apparatus unit A and the photosensitive member unit B is determined. Thereafter, the two units are connected with the first cover member 80 by the screws 96.

Similarly, as shown in FIG. 40, the pin 81a for placing the second cover member 81 in position on the developing apparatus unit A is fit-engaged with the positioning hole 50b provided in the developing roller frame 50, and the hole 81b for placing the second cover member 81 in position on the photosensitive member unit B is fit-engaged with the centering shaft 31 of the photosensitive drum 10 of the photosensitive member unit B, whereby the positions of the two units are determined. Thereafter, the developing apparatus unit A and the photosensitive member unit B are fixed to the second cover member 81 by resin bonding as follows.

Thereafter, the resin bonding portions of the developing apparatus unit A and the second cover member 81, separated in the above-described (First and Second Cover Member Detaching Process), are connected together by the following process.

(Resin Bonding Portion Connecting Process)

A method of connecting the separated resin bonding portions will be described with reference to FIGS. 41A, 41B, and 41C. FIG. 41A is a sectional view of the resin bonding portion separated by the above-described method.

The inner side of the cylindrical portion 81h of the resin bonding portion 81c is cut off, whereby the second cover member 81 is detached from the developer frame 21. In connecting the second cover member 81 and the developer frame 21, there is provided, as shown in FIG. 41B, a connecting member 110, and the cylindrical portion 81h of

the resin bonding portion **81c** of the second cover member **81** is press-fitted into a first press-fit portion **110a** provided in the connecting member **110**. Then, as shown in FIG. 41C, the cylindrical portion **21e** of the resin bonding portion **21c** of the developer frame **21** is press-fitted into a second press-fit portion **110b** provided in the connecting member **110**. Either of the second cover member **81** and the developer frame **21** may be press-fitted into the connecting member **110** first.

The first press-fit portion **110a** of the connecting member **110** is of a cylindrical configuration and has a size such that a close fit is effected between itself and the cylindrical portion **81h** of the second cover member **81**. Similarly, the second press-fit portion **110b** is of a cylindrical configuration and has a size such that a close fit is effected between itself and the cylindrical portion **21e** of the developer frame **21**.

Further, in this embodiment, the end surface **110c** of the connecting member **110** is placed in position by abutting the second cover member **81**. Similarly, the end surface **110d** of the connecting member **110** is placed in position by abutting the developer frame **21**. Thus, the positions of the second cover member **81** and the developer frame **21** are determined by the length of the connecting member **110**. Thus, the length of the connecting member **110** is determined such that the second cover member **81** and the developer frame **21** are placed at positions equivalent to those prior to dismantling. By using such a connecting member, the positioning and connection can be effected more easily.

By thus connecting the second cover member **81** with the developer frame **21**, the separated resin bonding portion can be connected easily without having to provide such processes as adhesion and post-treatment. There are no particular limitations regarding the material of the connecting member as long as it provides a fastening force strong enough to connect the second cover member **81** and the developer frame **21** according to the configuration and size of the press-fit portion.

Further, the replacement of the photosensitive drum **10** by a new one can be easily effected by the above-described remanufacturing method.

Also in the above construction, the connection of the resin bonding portion can be effected easily and reliably.

(Fixation Process)

Subsequently, the resin bonding portions of the photosensitive member unit **B** and the second cover member **81**, separated by the above-described (First and Second Cover Member Detaching Process), are connected by the following process.

FIG. 43A is a sectional view of a screw mounting hole **13s** (the prepared hole of a screw **97**) for mounting to the drum frame **13** the centering shaft **31**, which is the support member for rotatably supporting the photosensitive drum **10**. FIG. 43B is a sectional view of the screw mounting hole **13s** portion of the drum frame **13**, to which the centering shaft **31** is mounted in a state in which the second cover member **81** and the photosensitive member unit **B** are connected together by using a fixation member **114** described below.

At this time, the fixation member **114** (see FIG. 44A) shown in FIG. 43B has a flange portion **114a** whose diameter is larger than the diameter of a hole **81m** of the second cover member **81**, and an outer diameter smaller than the diameter of the hole **81m**. Further, the fixation member **114** has a cylindrical portion **114b** one end of which is connected with the inner diameter portion of the flange portion **114a**, and a bottom portion **114c** connected with the other end of

the cylindrical portion **114b** and equipped with a hole through which the screw **97** is to be passed. Further, the bottom portion **114c** is equipped with a hole **114d** through which the threaded portion of the screw **97** is passed.

When the screw **97** is screw mounted to the screw mounting hole **13s**, a head **97a** abuts the bottom portion **114c**. Then, the screw **97** biases the fixation member **114** in the direction indicated by an arrow **F**.

The inner peripheral surface of the cylindrical portion **114b** is larger than the outer diameter of the head **97a** of the screw **97**. Further, the height of the cylindrical portion **114b** is such that the head **97a** of the screw **97** does not protrude beyond the flange portion **114a**. As a result, as shown in FIG. 42, when the process cartridge **C** is attached to the apparatus main body **P**, the clearance **S** between the inner surface **504a** of the guide portion **504** of the main body **P** of the image forming apparatus and the longitudinal end portion of the process cartridge **C** is not reduced. That is, if the remanufactured cartridge **C** is attached to the main body **P** of the image forming apparatus, it is possible to secure the requisite clearance **S**.

Next, as shown in FIG. 43B, the fixation member **114** is fixed to the drum frame **13** by the screw **97**. At this time, the flange portion **114a** of the fixation member **114** abuts the second cover member **81**, applying pressure on the second cover member **81** toward the drum frame **13** in the direction indicated by the arrow **F**. At this time, there is a gap in the direction indicated by the arrow **F** between the bottom portion **114c** and the sheet metal portion **31a** of the centering shaft **31**.

Further, the centering shaft holding-down portion **81n** of the second cover member **81** holds the sheet metal portion **31a** of the centering shaft **31** between itself and the drum frame **13**, whereby the centering shaft **31** is fixed to the drum frame **13**. That is, by mounting the screw **97** to the screw mounting hole **13s**, it is possible to mount the second cover member **81** and the centering shaft **31** simultaneously to the drum frame **13**. As a result, even in the process cartridge remanufacturing method in which the resin bonding portions are once separated and connected again, it is possible to mount the photosensitive drum **10** firmly to the drum frame **13**. Thus, also in the remanufactured process cartridge **C**, the photosensitive drum **10** can be rotated without involving unevenness in rotation or the like, making it possible to provide a high quality image.

FIG. 44A is an outward perspective view of the fixation member **114**. FIG. 44B shows a fixation member **115** which is a modification of the fixation member **114**. The flange portion **115a** of the latter is not circular but consists of substantially rectangular protrusions extending radially from the cylindrical portion **115b**. The flange portions **115a** are provided on the cylindrical portion **115b** at two positions opposed to each other (that is, out of phase with each other by 180 degrees). Otherwise, the fixation member **115** is of the same construction as the fixation member **114**.

As described above, the flange portions **115a** apply pressure to press the second cover member **81** against the drum frame **13**, whereby the second cover member **81**, the centering shaft **31**, and the drum frame **13** can be firmly fixed together.

The material of the fixation member **114**, **115** used in the process cartridge remanufacturing method of this embodiment is metal or resin.

Further, the configurations of the fixation members **114** and **115** are not restricted to those shown in FIGS. 44A and 44B as long as they can mount the centering shaft **31** and the second cover member **81** to the drum frame **13**.

As described above, according to this embodiment, in the method of remanufacturing the process cartridge which is detachably mountable to the main body of the electrophotographic image forming apparatus and which is secured in position to the cover members by pouring molten resin into the resin bonding portions provided in the drum frame, after separation of the drum frame and the cover members, re-connection of the drum frame and the cover members can be effected easily and firmly. Further, a process cartridge of which the developer has been consumed to a degree such that image formation is no longer possible and which is, consequently, of no commercial value, can be easily filled with developer.

The order of the processes of the process cartridge remanufacturing method of the present invention is not restricted to the above order; it is also possible to change the order as appropriate.

It should be noted that the present invention covers all of the following cases:

(1) A case in which, remanufacturing of a process cartridge is conducted by using only components that are detached from a single process cartridge.

(2) A case in which, when, in the above case (1), some components cannot be re-used since they have reached their end of life, or they have suffered damage, and the like, the remanufacturing of a cartridge is conducted by using new components or recycled components detached from other cartridges.

(3) In remanufacturing a process cartridge, components detached from a plurality of process cartridges are classified into groups each of which consists of components of the same kind. Then, the requisite components are picked up from among the components thus classified, and remanufacturing of a cartridge is conducted by recycling these components.

(4) A case in which, when, in the above case (3), some components cannot be re-used since they have reached their end of life, or they have suffered damage, and the like, the remanufacturing of a cartridge is conducted by using new components.

The components as mentioned above are articles constituting a certain portion of a cartridge. Here, minimum units allowing dismantling are also included.

As described above, according to the present invention, in the process cartridge remanufacturing method in which the drum frame and the developing frame are connected to the second cover member by pouring molten resin into the resin bonding portions, the drum frame, the developing frame, and the second cover member can be re-connected easily and firmly.

While the invention has been described with reference to the structures disclosed herein, it is not confined to the details set forth and this application is intended to cover such modifications or changes as may come within the purpose of the improvements or the scope of the following claims.

This application claims priority from Japanese Patent Application No. 2004-121927 filed Apr. 16, 2004, and Japanese Patent Application No. 2005-112646 filed Apr. 8, 2005 which are hereby incorporated by reference herein.

What is claimed is:

1. A process cartridge remanufacturing method for a process cartridge detachably mountable to an electrophotographic image forming apparatus, the process cartridge comprising a first electrophotographic photosensitive drum, a first drum frame supporting the electrophotographic photosensitive drum, a first developing roller adapted to develop an electrostatic latent image formed on the electrophoto-

graphic photosensitive drum by using a developer, a developing frame supporting the developing roller and having a developer containing portion containing the developer, a first cover member positioned and configured to secure the developing frame and the first drum frame in position at one longitudinal end of the drum frame, a second cover member positioned and configured to secure the developing frame and the first drum frame in position at the other longitudinal end of the first drum frame, and a first drum supporting member which serves to support the first electrophotographic photosensitive drum on the first drum frame and which is fixed by a screw to a screw hole provided on the first drum frame at the other longitudinal end of the drum frame, the first drum frame and the developing frame being connected to the second cover member by pouring molten resin into resin bonding portions provided in the first drum frame, the developing frame, and the second cover member, the process cartridge remanufacturing method comprising:

- (a) a first cover member detaching step of detaching, at one longitudinal end of the process cartridge, the first cover member from the first drum frame and the developing frame;
- (b) a second cover detaching step of detaching, at the other longitudinal end of the process cartridge, the second cover member from the first drum frame and the developing frame;
- (c) a drum supporting member detaching step of detaching the first drum supporting member from the first drum frame;
- (d) a frame separating step of separating the developing frame and the first drum frame;
- (e) a developing roller detaching step of detaching the first developing roller from the developing frame;
- (f) a developer re-filling step of filling the developer containing portion with the developer from a developer supply port provided on the developing frame exposed by detaching the first developing roller from the developing frame;
- (g) a developing roller fixation step of mounting the first developing roller or a second developing roller to the developing frame filled with developer in said developer re-filling step or a different developer frame;
- (h) a drum mounting step of mounting, at the one longitudinal end, the first electrophotographic photosensitive drum or a second electrophotographic photosensitive drum to the first drum frame or a second drum frame;
- (i) a first frame connecting step of securing the drum frame undergoing the mounting performed in said drum mounting step and the developing frame undergoing the mounting performed in said developing roller fixation step in position at the one longitudinal end by the first cover member or a third cover member;
- (j) a second frame connecting step of securing the drum frame undergoing the mounting performed in said drum mounting step and the developing frame undergoing the mounting performed in said developing roller fixation step in position at the other longitudinal end by the second cover member or a fourth cover member;
- (k) a drum supporting member temporary mounting step of temporarily mounting the first drum supporting member or a second drum supporting member to support the electrophotographic photosensitive drum mounted in said drum mounting step at the other longitudinal end of the drum frame undergoing the mounting performed in said drum mounting step; and

23

(l) a second cover member mounting step of mounting the drum supporting member temporarily mounted in said drum supporting member temporary mounting step and the second cover member or a fourth cover member to the drum frame undergoing the mounting performed in said drum mounting step by mounting a fixation member to a mounting hole provided in the second cover member by using a screw in the event the second cover member is mounted to the drum frame undergoing the mounting performed in said drum mounting step and by 10 mounting the fixation member to a mounting hole provided in the fourth cover member in the event the fourth cover member is mounted to the drum frame undergoing the mounting performed in said drum mounting step.

2. A process cartridge remanufacturing method according to claim 1, wherein the fixation member has:

a flange portion that has a diameter larger than a diameter of the mounting hole of the second cover member and the fourth cover member and abuts the second cover member in the event the second cover member is mounted to the drum frame undergoing the mounting performed in said drum mounting step and abuts the fourth cover member in the event the fourth cover member is mounted to the drum frame undergoing the mounting performed in said drum mounting step; 20 a bottom portion which a head portion of the screw abuts; and

a cylindrical portion that connects the flange portion and the bottom portion and has a diameter larger than a 30 diameter of the head portion of the screw.

3. A process cartridge remanufacturing method according to claim 1, wherein the fixation member has:

a substantially rectangular flange portion that extends more greatly along a diameter direction of the hole than a diameter of the mounting hole of the second cover member and the fourth cover member and abuts the second cover member in the event the second cover member is mounted to the drum frame undergoing the mounting performed in said drum mounting step and abuts the fourth cover member in the event the fourth cover member is mounted to the drum frame undergoing the mounting performed in said drum mounting step; 35

a bottom portion which a head portion of the screw abuts; and

a cylindrical portion that connects the flange portion and the bottom portion and which has a diameter larger than a diameter of the head portion of the screw.

4. A process cartridge remanufacturing method according to claim 2 or 3, wherein, when the fixation member is mounted to the drum frame undergoing the mounting performed in said drum mounting step,

24

the flange portion presses the second cover member against the first drum supporting member in the event the second cover member is mounted to the drum frame undergoing the mounting performed in said drum mounting step and the first drum supporting member is temporarily mounted in said drum supporting member temporary mounting step,

the flange portion presses the second cover member against the second drum supporting member in the event the second cover member is mounted to the drum frame undergoing the mounting performed in said drum mounting step and second first drum supporting member is temporarily mounted in said drum supporting member temporary mounting step,

the flange portion presses the fourth cover member against the first drum supporting member in the event the fourth cover member is mounted to the drum frame undergoing the mounting performed in said drum mounting step and first drum supporting member is temporarily mounted in said drum supporting member temporary mounting step, and

the flange portion presses the fourth cover member against the second drum supporting member in the event the fourth cover member is mounted to the drum frame undergoing the mounting performed in said drum mounting step and second first drum supporting member is temporarily mounted in said drum supporting member temporary mounting step.

5. A process cartridge remanufacturing method according to claim 2 or 3, wherein a height of the cylindrical portion is larger than a height of the head portion of the screw.

6. A process cartridge remanufacturing method according to claim 1, wherein a material of the fixation member is a metal.

7. A process cartridge remanufacturing method according to claim 1, wherein a material of the fixation member is a resin.

8. A process cartridge remanufacturing method according to claim 1, wherein, said drum mounting step mounts the second electrophotographic photosensitive drum, wherein the second electrophotographic photosensitive drum is a new electrophotographic photosensitive drum.

9. A process cartridge remanufacturing method according to claim 1, wherein said second frame connecting step secures the drum frame undergoing the mounting performed in said drum mounting step and the developing frame undergoing the mounting performed in said developing roller fixation step in position at the other longitudinal end by the second cover member detached in said second cover member detaching step.
